[57] CLAIM

The ornamental design for a nutcracker cup, as shown and described.

DESCRIPTION

FIG. 1 is a side elevational view of a nutcracker cup, showing my new design.

FIG. 2 is a top plan view thereof.

FIG. 3 is a bottom plan view thereof.

FIG. 4 is a rear elevational view thereof.

FIG. 5 is a front elevational view thereof.

FIG. 6 is a section taken at line 6—6 in FIG. 2 and viewed in the direction of the arrows.

FIG. 7 is a section taken at line 7—7 in FIG. 2 and viewed in the direction of the arrows.

The broken lines are for illustrative purposes only and form no part of the claimed design.
